W. A. LARNED

METHOD OF CONTROLLING THE ELASTICITY OF AN ELASTIC METAL STRINGING

Filed July 17, 1923

INVENTOR,
William A. Larned,
BY Howard S. Smith,
ATTORNEY.

UNITED STATES PATENT OFFICE.

WILLIAM A. LARNED, OF SUMMIT, NEW JERSEY, ASSIGNOR TO THE DAYTON STEEL RACQUET COMPANY, OF DAYTON, OHIO, A CORPORATION OF OHIO.

METHOD OF CONTROLLING THE ELASTICITY OF AN ELASTIC-METAL STRINGING.

Application filed July 17, 1923. Serial No. 652,093.

To all whom it may concern:

Be it known that I, WILLIAM A. LARNED, a citizen of the United States, residing at Summit, in the county of Union and State of New Jersey, have invented certain new and useful Improvements in a Method of Controlling the Elasticity of an Elastic Metal Stringing, of which the following is a specification.

10 This invention relates to new and useful improvements in an elastic metal stringing, and has particular reference to a method of increasing the elasticity or playability of a metal tennis-racket stringing by varying the lay or pitch of the latter and the diameter of the core around which it is wound.

15 It is the object of the present invention to provide an elastic metal stringing which has all the advantages of gut in the way of large elasticity and a small amount of elongation, by lengthening the lay of the wire and increasing the diameter of the core. This method of producing an elastic metal stringing also increases and economizes production.

In the accompanying drawings illustrating my invention, Figure 1 is a perspective view of a standard lay, grouped, nine wire stringing wound around a No. 7 core. Figure 2 is a cross sectional view taken through said stringing on the line 2—2 of Figure 1. Figure 3 is a perspective view of a long lay, grouped, nine wire stringing wound around a No. 7 core. Figure 4 is a cross sectional view of the same taken on the line 4—4 of Figure 3. Figure 5 is a perspective view of the long lay stringing wound around a No. 10 core. Figure 6 is a cross sectional view of the same taken on the line 6—6 of Figure 5. Figure 7 is a perspective view of the long lay stringing after the No. 10 core has been removed and the stringing stretched to the blocking point. Figure 8 is a cross sectional view taken on the line 8—8 of Figure 7. And Figure 9 is a plan view of a tennis racket containing my long lay stringing which has been wound around a No. 10 core.

Throughout the specification and drawings, similar reference characters denote corresponding parts.

In a detailed description of the embodiment of my invention illustrated in the accompanying drawings, the numeral 1 designates a standard lay stringing consisting of three groups of three wires each, which have been wound around a No. 7 core designated by the numeral 2. By changing the pitch of this stringing from 12 to 8, I produce the stringing 3 in Figure 3, which is known as long lay. In Figures 3 and 4 I show this long lay stringing wound around a No. 7 core, which is designated by the numeral 4. In Figure 5 a long lay stringing 5, similar to the stringing 3, is shown, except that it has been wound around a No. 10 core designated by the numeral 6. Figure 9 shows this stringing in a tennis racket 7.

55 After the core had been removed from each one of the stringings 1, 3 and 5, and they were stretched to the blocking point, or a point beyond which they have a maintained elasticity due to the torsional reaction of the groups of wires upon each other, tests were made upon them with an Olsen testing machine, which tests showed that the elasticity and elongation or set of the stringing is directly controlled by the pitch or lay of the wire and the size of the core employed.

60 Under a 60 pound blow, which is the force with which a ball is hit by the average tennis player, the tests showed that the standard lay stringing 1, wound around a No. 7 core, had an elasticity of 6.9% and an elongation of 1.7%. Under the same blow the long lay stringing 3 that had also been wound around a No. 7 core, had an elasticity of 6.2% and an elongation of .8%. Where a No. 10 core had been used with the long lay stringing 5, the tests showed that 65 under a blow of 60 pounds, the said stringing had an elasticity of 8% and an elongation of 1.7%. Such a stringing gave even better results than gut without its disadvantages, for under a 60 pound blow the tests showed that the gut stringing only had an elasticity of 6.6% and an elongation of 2.1%.

70 It is thus possible by increasing the pitch or lay of the wire and the diameter of the core around which it is first wound, to produce an elastic metal stringing whose elasticity or playability may be increased in certain instances beyond that of gut, and having an elongation below that of the latter in those instances. Furthermore, by in-

creasing the pitch or lay of the stringing, production has been increased and economized.

Having described my invention, I claim:

- 5 1. The method of controlling the elasticity of a metal stringing comprising a number of wires wound together, which consists in varying the pitch on which the wires are wound.
- 10 2. The method of controlling the elasticity of a metal stringing comprising a number of wires that are first wound around a core that is later removed, which consists in varying the diameter of said core.
- 15 3. The method of controlling the elasticity of a metal stringing comprising a number of wires that are first wound around

a core that is later removed, which consists in varying the pitch on which the wires are wound and changing the diameter of said core. 20

4. The method of increasing the elasticity, and reducing the elongation, of a metal stringing comprising a number of wires that are first wound around a core that is later removed, which consists in increasing the lay of said wires and the diameter of the core. 25

In testimony whereof I have hereunto set my hand this 13th day of July, 1923.

WILLIAM A. LARNED.

Witness:

WATSON WASHBURN.
